MACHINE FOR FORMING FLAT COILS
OF WIRE

Frank A. Genua, Waterbury, Conn.

Application January 18, 1949, Serial No. 71,510

2 Claims. (Cl. 153—64)

1

This invention relates to machines for making flat coils of wire, and more particularly to a machine adapted to wind spring or other resilient wire into coils having accurately formed and aligned outside turns which are located in parallel planes.

One object of this invention is to provide a machine of the above nature in which the coil is formed by overbending the successive turns about a mandrel whereby the inherent resilience of the wire will cause the opposite sides of the coils to lie substantially in parallelism.

Another object is to provide a machine of the above nature wherein the coil forming mandrel is recessed so as to permit the turns of the wire to be pressed further inwardly than their final position by a pair of opposed dies, and thus acquire the desired set.

Another object is to provide a machine of the above nature wherein excessive overbending of the wire is prevented by means of an inner abutment which is provided by a central web section of the mandrel.

A further object is to provide a machine of the above nature which will be simple in construction, inexpensive to manufacture, easy to install and operate, compact, and very efficient and durable in use.

With these and other objects in view, there has been illustrated on the accompanying drawing one form in which the invention may conveniently be embodied in practice.

In the drawings,

Fig. 1 is a front view of the improved machine showing the dies in separated position.

Fig. 2 is a front view of a portion of the same, on an enlarged scale, showing the dies in their inner position, and pressing the wire upon the mandrel.

Fig. 3 is a perspective view of the same, but showing the dies in separated position.

Fig. 4 is a right hand side view of the machine, partly broken away.

Fig. 5 is a view of the intermittent drive mechanism for the mandrel, taken substantially on the line 5—5 of Fig. 4.

Fig. 6 is a fragmentary cross-sectional view, taken substantially on the line 6—6 of Fig. 4, showing the gearing and the anti-backlash mechanism.

Fig. 7 is a plan view of the machine, partly broken away.

Fig. 8 is a fragmentary rear view of the same, showing the stop mechanism for the mandrel.

2

Fig. 9 is a perspective view of a portion of the finished coil of wire.

Referring now to the drawings in which like reference numerals denote corresponding parts throughout the several views, the numeral 10 indicates a recessed mandrel having a flat central web section 11 which has opposite enlarged parallel rounded edge portions 12, whereby a cross-section of the mandrel resembles the shape of a dumbbell (Fig. 2).

The mandrel 10 is mounted upon the forward end of a horizontal shaft 13 which is journaled in the upper central portions of front and rear walls 14, 15, of a U-shaped frame 16, and is adapted to be intermittently rotated so as to wind wire W into a flat-sided coil C on said mandrel.

The mechanism for rotating the shaft 13 comprises a pair of mutilated gears 17, 18 (Fig. 5) secured respectively on the horizontal shaft 13 and on a drive shaft 19 which is carried in the front and rear walls 14, 15 below the horizontal shaft 13. The drive shaft 19 extends outwardly of the rear wall 15 and carries a pulley 20, which is adapted to be engaged by a belt driven from any suitable source of power, not shown.

The mutilated gear 17 is provided with a pair of diametrically opposed toothless segments 21, 21 whereas the lower mutilated gear 18 has a single toothless segment 22 extending over approximately one-half of its circumference, so that when the drive shaft 19 is constantly rotated, the upper shaft 13 will be driven in successive steps of 180 degrees each, with dwell periods between the steps.

In order to cause the teeth of the upper gear 17 to engage with the teeth of the lower gear 18 for initiating each step of the rotation, the upper gear 17 is provided with a pair of side pins 23, 23 disposed adjacent the respective toothless segments 21 and in such a position as to be engaged by a dog 24 secured to the lower gear 18.

The side pins 23 are arranged in the same plane as the recessed mandrel 10 so that when said mandrel is rotated to a vertical position, the driving connection between the mutilated gears 17 and 18 will be broken and will remain broken until the lower gear 18 has made another half-revolution so as to bring the dog 24 into engagement with one of the side pins 23, and thus initiate another half-revolution of the mandrel 10.

In order to prevent the mandrel 10 from moving past a vertical position at the beginning of each dwell period, provision is made of a stop mechanism comprising a cam 25 (Fig. 8), which

is secured upon the shaft 13 outwardly of the rear wall 15. The cam 25 has a pair of diametrically opposed recesses 26 which are adapted to be engaged by a roller 27 carried by an inclined spring-pressed plunger 28, which is slidably mounted in a bracket 29 on the rear wall 15. The stop cam 25 is so adjusted with relation to the shaft 13, as to prevent overriding of the upper mutilated gear 17 when the latter comes to its dwell position.

However, when the driving connection between the gears 17, 18 is reestablished, the spring-pressed plunger 28 will yield so that the roller 27 may ride out of the recess 26 in which it is disposed, and thus permit the stop cam 25 to resume rotation.

In order to insure against backward rotation of the mandrel 10 during the dwell period, provision is made of an anti-backlash cam 30 (Fig. 6) secured to the shaft 13 inwardly of the rear wall 15. The cam 30 is provided with a pair of diametrically-opposed radial steps 31, 31 adapted to be intermittently engaged by a pawl 32 which is mounted on a stationary pivot 33 and which is urged against the periphery of said cam by means of a spring 34.

The radial steps 31 are so disposed with relation to the shaft 13 that the pawl 32 will drop against one of said steps at the same instant that the mandrel 10 arrives at a vertical position, thus preventing any backward movement of said mandrel.

The machine is so constructed that the wire W will approach the recessed mandrel 10 in a path which is substantially tangent to said mandrel, said wire being guided by means which comprises a forwardly-projecting bracket 35 (Figs. 1, 4, and 7) secured to the top center portion of the front wall 14, and a horizontally-adjustable slotted guide 36 secured to the front face of said bracket by means of a clamping screw 37.

The wire W is slidably confined between a reduced inner end portion 38 (Fig. 3) of the guide 36 and the front face of the bracket 35, said front face being disposed in substantially the same plane as the front end of the shaft 13.

The bracket 35 is also provided with a screw having an apertured head 39 which serves as a guide for the wire W prior to its entrance between the reduced guide portion 38 and the bracket 35.

The machine may be further provided, if desired, with an additional guide 40 which is secured to a post 41 on the front wall 14.

In order to slide the coil C progressively off from the mandrel 10 as new turns of wire are formed thereon, provision is made of a slotted cam piece 42 which is adjustably secured to the front of the bracket 35 by means of a clamping screw 43. The lower end of the cam piece 42 has an integral inclined stripper tongue 44 which has a camming action against each new turn of the wire as it is rotated upon the mandrel 10, thus urging it outwardly of said mandrel.

In order to impart a 180 degree set to the wire W about the enlarged edge portions 12 of the mandrel 10, provision is made of a pair of opposed reciprocating dies 45, 45 (Fig. 2) which have narrow end faces 46 for pressing each new turn of wire into the recessed sides of the mandrel 10 during each dwell period of said mandrel. Thus, it will be seen that the wire will be bent more than 180 degrees about the enlarged edge portions 12 to produce a permanent set of the wire of 180 degrees, so that the sides of

the coil C will be perfectly flat when released by the dies 45.

The dies 45 are preferably operated by means of a pair of horizontal rectangular supporting slides 47, 47 carried in aligned horizontal guideways 48, 48 in a pair of brackets 49, 49 which are secured to the upper and outer portion of the front wall 14, a plurality of retainer plates 50, 50 being provided for holding the slides 47 in position.

The slides 47 have vertical slots 51, 51 formed in their inner faces, said slots being engaged with eccentric pins 52, 52 upon the forward ends of a pair of horizontal upper shafts 53, 53 which are supported in the front and rear walls 14, 15 (see Fig. 4). Thus, rotation of said shafts 53 will reciprocate the slides 47 and the dies 45 thereon—the pins 52 being so arranged that the dies 45 will move toward each other so as to simultaneously engage the wire at the opposite sides of the mandrel 10.

The shafts 53 are provided with a pair of gears 54, 54 which are connected with a gear 55 on the drive shaft 19 by means of a pair of idler gears 56, 56 supported on a pair of lower shafts 57, 57.

It will be understood that the operating mechanism for the dies 45 is so proportioned and adjusted as to cause said dies to engage a new turn of wire upon the mandrel 10 during each dwell period in the rotation of said mandrel, thus insuring that each successive turn of the wire in the coil C will receive the proper set.

Operation

In operation, the leading end of the wire W will first be inserted in the guides 40 and 39 and between the adjustable guide 36 and the bracket 35, and then engaged with the mandrel 10, as for example by bending one turn of the wire manually about said mandrel. The drive pulley 20 will then be driven from any suitable source of power so as to rotate at a substantially constant speed in clockwise direction, as viewed in Fig. 1.

This will cause the recessed mandrel 10 to rotate counterclockwise in a series of 180 degree steps having interposed dwell periods during which the mandrel 10 will be disposed in a vertical position, as seen in Fig. 1.

During each of the dwell periods, the dies 45 will approach the mandrel 10, as hereinbefore described, so as to press the sides of the newly formed turn of wire into the recessed sides of the mandrel 10 adjacent the web section 11. The dies 45 will then separate, so as to permit another 180 degree movement of the mandrel 10, after which the movement of the dies 45 will be repeated.

Each new turn of wire will, of course, come into engagement with the stripper tongue 44 at each movement of the mandrel 10, so that the coil C will be progressively urged off the mandrel 10, and each new turn of wire will be formed accurately in position to be engaged by the die faces 46.

The aforesaid operation will result in a coil having accurately formed parallel flat sides joined by opposite semi-circular edge portions.

It will be seen that the action of the dies 45 will bend the wire more than 180 degrees around the enlarged edge portions 12 of the mandrel 10, thus overbending the wire to a predetermined extent and yet permanently setting the wire in a bend of only 180 degrees.

Although slight reverse bends in the wire will occur adjacent the edges of the dies 45 during manufacture, as shown in Fig. 2, these reverse bends are attended by no strain beyond the elastic limit of the wire, and disappear as soon as the dies 45 are withdrawn.

The operation of the machine may be continued until such time as the coil C has attained the desired length, at which time it may be cut off the mandrel 10 by any suitable cutting means, not shown.

While there has been disclosed in this specification, one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a machine for forming flat-sided coils of resilient wire, a rotatable mandrel having enlarged cylindrical substantially parallel edge portions joined by a flat, solid, anvil web section providing recesses in the sides of said mandrel, wire guide means, mechanism for rotating said mandrel to wind wire from said guide means into a coil on said mandrel, and means for pressing

said wire into said recesses against said web section inwardly of said enlarged edge portions, whereby said wire may be overbent around said edge portions so as to receive a predetermined permanent set.

2. In a machine for forming flat coils of resilient wire, a mandrel having a pair of enlarged substantially cylindrical parallel edge portions joined by a flat solid, anvil web section, means for winding wire over said edge portions to form a coil on said mandrel, and means for pressing the wire on said mandrel inwardly against both sides of said web section between said edge portions, whereby the wire may be bent more than 180 degrees around each edge portion so as to receive a permanent set of 180 degrees.
